DISPENSING-DISPLAY STAND

Severin A. Prag, St. Louis, Mo.

Application December 5, 1945, Serial No. 632,875

2 Claims. (Cl. 248—97)

1

This invention relates to dispensing-display stands, particularly the collapsible type of stand, in which the wares to be sold are displayed and from which customers help themselves.

The main object of the invention is to produce such a stand which can be collapsed with the minimum of time and effort, and it is especially applicable for selling newspapers, though not limited to this use. As is well known by newspaper dealers, it is important that their display stands be adapted for quick collection after the papers have been sold, and also that a single person be able to collect a considerable number of the stands for return to the dealer. My stand meets these requirements by reason of the ease with which it may be collapsed and placed on the collector's truck and its light weight. A further advantage of my stand is that, besides being weatherproof itself, it also provides protection for the wares being displayed or sold out of doors in inclement weather by means of its cover, which automatically falls into place after each sale unless fastened in raised position.

In the drawings—

Fig. 1 is a perspective view of the stand in unfolded position.

Fig. 2 is an enlarged, vertical section thereof, taken on line 2—2, Fig. 1, showing particularly the folding mechanism.

Fig. 3 is an elevational rear view of the stand in collapsed condition.

Fig. 4 is a vertical section thereof taken on line 4—4, Fig. 3.

While I have illustrated and will describe the invention particularly as a newspaper stand, it is to be understood that it could be used to equal advantage for the display and sale of various other small articles, and I prefer to construct it entirely of metal, except the sack. It will be noted that in the drawings (Figs. 1 and 2) I have shown a coin box attached to the stand, but the coin box is the subject of a separate application and will not be referred to herein. The stand can be used equally well without the coin box.

I will first describe the stand as it appears when unfolded, and in this position the invention comprises a frame including a pair of diagonal side members 1 which also serve as supporting legs, a cross bar 2 connecting the members 1 at their upper ends, a cross bar 3 connecting them at their lower ends, and a cross bar 4 connecting them at a point somewhat above the center of said members 1. The parts thus far mentioned are rigidly secured together, preferably by welding. Slightly spaced above the cross bar 4 a rotatable

2

cross bar 5 extends between the diagonal members 1, and slightly spaced below the cross bar 4 a rotatable cross bar 6 extends between said diagonal members.

5 A diagonal supporting member 7 is rigidly secured to the center of the rotatable cross bar 6, said supporting member 7 terminating at its lower end in an arched portion having a pair of legs 8 for additional support. Each leg 8 is provided 10 at its lower end with a clamp 9 adapted to engage a diagonal member 1 when the stand is collapsed, as will be presently described.

Rigidly secured to the front of the cross bar 4 a pair of rings 10 extend forwardly at right angles 15 to said cross bar 4. A rectangular frame, for the support of the newspaper sack 11, comprises a rear rod 12, end rods 13, and a front rod 14, the rear rod 12 being swingable in the rings 10. The newspaper sack 11 is suspended from the rods 12, 20 13, and 14, to which it is fastened by means of clasps 15, or in any preferred manner.

An arm 16 is pivotally secured at 17 to each of the end rods 13 and extends diagonally to one of the diagonal side members 1, said arm being provided 25 with a slot 18 by means of which the arm 16 is slideable on a pin 19 on the said diagonal member 1. The slot 18 terminates at its lower end in an enlarged opening having a shoulder 20 for engagement with the pin 19 to hold the arm 30 16 stationary against sliding movement when desired.

A sheet metal cover 21 for the sack 11 is rigidly secured to the rotatable cross bar 5 so that it will swing with the rotation of said cross bar. The 35 lid 21 is of such dimensions that it will fit loosely within the aperture formed above the cross bar 5 by the diagonal members 1 and the cross bar 2, and at its forward edge it is provided with a clamp 22 adapted to engage the cross bar 2 to 40 hold said lid in its raised position (Fig. 1).

In operation the procedure is as follows: Suppose the stand is in its unfolded position, as shown in Figs. 1 and 2, and the intention is to collapse it. The supporting member 7 and the legs 8 are 45 pushed forward until the clamps 9 engage the diagonal members 1. The pins 19 are disengaged from the shoulders 20, which permits the arms 16 to slide upon the diagonal members 1 by virtue of the slots 18, which has the effect of drawing 50 down the end rods 13 of the rectangular frame through the pivotal connections at 17, and also through the swinging engagement of the rear rod 12 with the rings 10, so that the said rectangular frame assumes a position practically parallel with 55 the diagonal members 1. At this point the stand

has been collapsed to the position shown in Fig. 4.

Now suppose it is desired to open the stand for use. The diagonal members 1 are disengaged from the clamps 9 and the legs 8 are pulled back to the position shown in Fig. 2, and when they have reached this point further backward movement is prevented by a stop member 23 which is secured to the rotatable cross bar 6 and comes to rest against the cross bar 4.

The next step is to open the sack 11, and this is accomplished by drawing upward the end rods 13 until the shoulders 20 engage the pins 19. This movement causes the rod 12 to swing in the rings 10 and extends the bars 13 and 14 to their horizontal positions, which obviously causes the sack 11 to assume the unfolded position shown in Figs. 1 and 2.

Sometimes in case of inclement weather it is necessary to close down the cover 21 over the sack 11, and this is done by merely disengaging the clamp 22 from the cross bar 2 and swinging said cover downwardly until it rests upon the rods 12, 13, and 14. This downward movement of the cover 21 is illustrated in dot and dash lines in Fig. 2.

I claim:

1. A dispensing-display stand comprising in its unfolded position a pair of diagonal side members and a swingable supporting member, a member rigidly connecting said diagonal members, a sack and means on said connecting member for swingably supporting said sack, slotted elements adapted for sliding movement upon said diagonal members for collapsing said sack, and means for preventing such movement, said diagonal members extending upwardly beyond said sack and being provided at their upper ends with a connecting

member, and a swingable cover for said sack adapted to be engaged with said connecting member to retain said cover in raised position, said stand being adapted to collapse with its parts in substantially parallel positions.

2. A dispensing-display stand comprising in its unfolded position a pair of diagonal side members and a swingable supporting member provided with a stop for limiting its movement, a rigid connecting member between said diagonal members, a sack and means on said rigid member for swingably supporting said sack, slotted elements pivotally attached to said sack-supporting means and adapted for sliding movement upon said diagonal members for collapsing said sack, means for preventing said movement, and a swingable cover for said sack, said diagonal members extending upwardly beyond said sack and being provided at their upper ends with a horizontal connecting member, and said swingable cover having a clamp for engagement with said horizontal connecting member adapted to retain said cover in raised position, said stand being adapted to collapse with its parts in substantially parallel positions.
